UNITED STATES PATENT OFFICE.

ALLAN K. BOWMAN, OF PITTSBURG, PENNSYLVANIA.

TOBACCO-PIPE.

SPECIFICATION forming part of Letters Patent No. 699,480, dated May 6, 1902.

Application filed April 10, 1901. Serial No. 55,171. (No model.)

To all whom it may concern:

Be it known that I, ALLAN K. BOWMAN, a citizen of the United States, and a resident of Pittsburgh, in the county of Allegheny and 5 State of Pennsylvania, have invented a new and Improved Tobacco-Pipe, of which the following is a full, clear, and exact description.

This invention relates to a tobacco-pipe with certain novel constructions by which 10 the smoke is rendered pure, free from nicotine as it passes to the smoker, and by which all liquid matter accumulating in the stem is safely retained therein until the stem is opened to clean it.

15 The invention involves various novelties of form and arrangement, which will be fully developed hereinafter.

This specification is a specific description of two forms of the invention, while the claims 20 are definitions of the actual scope thereof.

Reference is to be had to the accompanying drawings, forming a part of this specification, in which similar characters of reference indicate corresponding parts in all the views.

25 Figure 1 is a side view of my invention. Fig. 2 is a longitudinal section thereof. Fig. 3 is a detail view of the gauze tube. Fig. 4 is a detail section of the plug which holds said tube. Fig. 5 is a detail view of the baffle- 30 plate in the gauze tube. Fig. 6 is a sectional view showing a slight modification of the invention, and Fig. 7 is a detail of the mouth-piece shown in Fig. 6.

a indicates the bowl of the pipe, which is 35 preferably of spherical form.

a' indicates a cover or lid of the bowl which is formed with a slot a², extending across its circumference. In this slot is received a headed pin a³, fastened to the bowl.

40 A catch of any suitable form may be provided for holding the cover in a closed position. When it is desired to open the cover, it may be slid on the bowl, the movement of the cover being guided by the walls of the slot

45 engaging the pin a³, thus sliding the guide sidewise and extending the opening in the top of the bowl a.

The stem b of the pipe is screwed onto the bowl, as shown best in Fig. 2, and the mouth-piece c is connected to the stem by a coupling comprising a threaded band d and a web or disk d', projecting inwardly therefrom and

lying between the parts b and c. This web d' serves a function which will be hereinafter brought out. Establishing communication 55 between the bowl a and the stem b is a tube e, which is screwed or otherwise fastened in the bowl, as shown in Fig. 2, and has the end within the bowl cut square, so as to form a shoulder at the upper side of the tube, this 60 shoulder receiving the pressure of the tobacco when packed in the bowl and causing the tobacco to lie loose immediately before the tube. This avoids clogging the tube.

The interiors of the stem b and mouthpiece 65 care provided with absorbent linings f. These linings are preferably of blotting-paper or the like, so that the nicotine and other liquid and like substances accumulating in the stem and mouthpiece will be absorbed and retained by 70 these linings. The linings are not absolutely essential to my invention; but I consider them advantageous, since they constitute an assurance of effectiveness. Within the stem I arrange a strainer in the form of a woven metallic tube, which acts to strain and break up the smoke into small particles as it passes therethrough, thereby robbing it of its deleterious qualities. This strainer-tube is indicated at g in the drawings. It is constructed, 75 preferably, of aluminium, and it lies within the stem b, the tube extending from the outer end of the tube e to engagement with an enlargement h' on the tube h, which is fitted within and held by the web d' of the collar or 80 sleeve d. Approximately at the center of the tube g is arranged a baffle-plate g' of the peculiar form shown in Fig. 5, the peripheral prongs on the baffle-plate being engaged in the mesh of the tube g to hold the baffle-plate 85 in place. The mouthpiece c has a contracted portion or mouthpiece proper, c', and the inner extremity of this has a small tubular extension c² projecting into the mouthpiece c to prevent liquid from passing from the mouth-piece into the mouth of the smoker.

Now with the arrangement above described it is clear that the tobacco cannot be so crowded around the tube e as to clog the bowl of the pipe and prevent easy smoking. As the 100 smoke passes through the tube e into the woven tube g it is caused to pass out and then back into the woven tube around the baffle-plate g' and through the tube h to the

mouthpiece. This passage of the smoke through the woven tube *g* will divide the smoke up into fine particles and collect from it the suspended poisonous substances. This 5 tube *g* will also cool the smoke by breaking it up into small particles, and thus facilitate the reduction of its temperature. Any liquid that accumulates in the stem or mouthpiece will be absorbed by the pads *f*. The 10 smoke passes from the tube *h* to the contracted portion *c'* of the mouthpiece and then to the mouth of the smoker.

The form of my invention shown in Figs. 6 and 7 illustrates a modified arrangement of 15 the mouthpiece in which the extremity of the mouthpiece is curved inward, as at *c'*, to conform to the shape of the teeth of a person, so that the pipe may be held easily in the mouth without danger of dropping it and without 20 the exercise of much strength. In other respects the invention shown in Fig. 6 is the same as that shown in the other figures. This improved mouthpiece is adaptable to pipes with either straight or crooked stems.

25 Having thus described my invention, I claim as new and desire to secure by Letters Patent—

1. A pipe having a spherical bowl cut off at the top, a cover for said top, the cover being 30 concavo-convex in form and having a slot therein, and a guide device fastened to the bowl and loosely received in the slot.

2. A pipe having a strainer-tube of woven fabric arranged therein and adapted to have 35 the smoke drawn through it, and a baffle-plate situated in the tube.

3. A pipe having its stem provided with a strainer in the form of a foraminous tube into which the smoke-passage of the bowl leads, 40 said tube being provided with a baffle-plate at about the center of its length.

4. A pipe having a bowl, a stem fastened thereto, a mouthpiece fastened to the stem, a

coupling for joining together the stem and mouthpiece, the coupling comprising a web 45 projecting between said parts, a smoke-tube held in the web, and a strainer in the form of a foraminated tube held in the stem and mounted on said smoke-tube.

5. In a pipe, a stem provided with an apertured web extending across its bore, a short tube carried by the web, and a tubular strainer into the outer end of which the short tube projects, said strainer being provided with a transverse partition. 55

6. A pipe comprising a bowl having a tube leading therefrom, a stem secured to the bowl, a mouthpiece secured to the stem, an apertured web arranged between the stem and mouthpiece, a short tube secured in the aperture of the web, and a tubular strainer into the inner end of which the tube of the bowl projects, the said strainer being provided with a transverse partition and having its outer end fitting upon the said short tube, as 60 set forth. 65

7. A pipe, comprising a bowl having a tube leading therefrom, a stem secured to the bowl, a mouthpiece, a threaded band engaging the stem and mouthpiece and securing them together, said band being provided with a web having a central aperture, a short tube having a reduced end fitting in the aperture of the web, and a tubular strainer into the inner end of which the tube of the bowl extends, the said strainer being provided with a transverse partition and having its outer end fitting upon the inner end of the said short tube, as set forth. 75

In testimony whereof I have signed my name to this specification in the presence of two subscribing witnesses.

ALLAN K. BOWMAN.
